PAGE 2

FIG. 5.

FIG. 6.

FIG. 7.

Figure 1 is a perspective view of the ambulatory aircraft loading unit embodying my new design, the cargo platform being shown in its fully elevated position.

Figure 2 is a top plan view of the unit illustrated in Figure 1.

Figure 3 is a side elevational view from the right of the unit as viewed in Figure 1, and the fully lowered position of the cargo platform being indicated in dot-and-dash lines.

Figure 4 is a perspective view of the ambulatory aircraft loading unit as viewed from the diametrically opposite vantage point from that employed in Figure 1.

Figure 5 is a side elevational view of the unit taken from the left hand side as viewed in Figure 1.

Figures 6 and 7, respectively, are front and rear end elevational views of the unit as shown in Figure 1.

The essential features of my design reside in those portions shown in full lines.

This application is a continuation-in-part of my co-pending application for United States Letters Patent Serial No. 42,744, filed August 27, 1956 now abandoned, for ambulatory aircraft loading unit.

I claim:

The ornamental design for an ambulatory aircraft loading unit as shown and described.
